UNITED STATES PATENT OFFICE.

DAVID L. PENROD, OF ALTA, UTAH.

AMALGAMATING-MILL.

1,230,770.

Specification of Letters Patent. Patented June 19, 1917.

Application filed January 27, 1917. Serial No. 144,878.

To all whom it may concern:

Be it known that I, DAVID L. PENROD, a citizen of the United States, residing at Alta, in the county of Salt Lake and State of Utah, have invented certain new and useful Improvements in Amalgamating-Mills; and I do hereby declare the following to be a full, clear, and exact description of the invention, such as will enable others skilled 10 in the art to which it appertains to make and use the same.

The invention relates to improvements in amalgamating mills.

The object of the present invention is to 15 improve the construction of amalgamating mills and to provide a simple, practical and comparatively inexpensive construction capable of thoroughly subjecting the material to the action of the mercury and of automatically returning the mercury to the material after the mercury has passed through 20 the machine so that a quantity of mercury may be successively used in the machine as often as desired to obtain the required 25 values.

With these and other objects in view, the invention consists in the construction and novel combination of parts hereinafter fully described, illustrated in the accompanying 30 drawing, and pointed out in the claims here- 35 to appended; it being understood that various changes in the form, proportion, size and minor details of construction, within the scope of the claims, may be resorted to without departing from the spirit or sacrificing any of the advantages of the invention.

In the drawings

Figure 1 is a front elevation of an amalgamating mill constructed in accordance with 40 this invention, the main casing of the mill being in section and parts being broken away.

Fig. 2 is a vertical sectional view on the line 2—2 of Fig. 1,

Fig. 3 is a similar view on the line 3—3 of Fig. 1,

Fig. 4 is a vertical sectional view on the line 4—4 of Fig. 1,

Fig. 5 is a detail view partly in section illustrating the manner of mounting the rotary mercury spray pipes,

Figs. 6 and 7 are detail views illustrating

the construction for operating the mercury spray pipes,

Fig. 8 is a plan view of a portion of the mill partly in section illustrating the arrangement of the troughs and the spray pipes.

Fig. 9 is a detail sectional view on the line 9—9 of Fig. 4.

Like numerals of reference designate corresponding parts in the several figures of the drawings.

In the accompanying drawings in which 65 is illustrated the preferred embodiment of the invention, the amalgamating mill which is preferably provided with a main casing or housing 1 comprises in its construction an upper inlet sand trough or flume 2 constituting a sluice way and located above a baffle casing 3 provided with horizontal baffle plates 4 arranged in spaces and forming longitudinal passages and alternately terminating short of the opposite ends of the 70 casing 3 to connect the adjacent passages for causing the material to travel back and forth through the baffle casing from the top to the bottom thereof. The material and the mercury are caused to fall at the outlet 75 end of the passages of the baffle casing for causing a thorough mixing or intermingling of the sand and the mercury and the latter is delivered into the inlet trough or sluice way 2 by inclined rotary mercury spray pipes 5. 80 The mercury spray pipes 5 which are arranged in opposite sets or series extend downwardly and inwardly and are provided with perforations 6 for the discharge 85 of the mercury and they are also provided at their inner lower ends with suitable closures 7 for preventing the escape of mercury through the inner or lower end of the spray pipes. The spray pipes which are journaled in suitable bearings are adapted 90 when rotated to effect a distribution of the mercury uniformly throughout the material passing through the inlet trough or sluice way. The inlet trough or sluice way is provided at its inner end with an outlet 8 leading 95 into the baffle casing and the said trough is also provided at the outlet with an upwardly projecting flange 9 forming a stock or riffle and adapted to collect coarse gold and prevent the same from passing through 100 the baffle casing.

105

The mercury spray pipes which may be of any desired number are arranged at intervals and are equipped with gear wheels 10 at a point intermediate of their ends and receive arms or branches 11 of relatively fixed pipes 12 extending from mercury troughs 13 located above and at opposite sides of the inlet trough or sluice way. The stationary pipes 12 extend downwardly and the branches 11 project inwardly into the outer ends of the spray pipes 5. The gears 10 are located adjacent to the outer ends of the spray pipes and the latter are provided throughout the portion of their length with the perforations 6. The rotary movement of the spray pipes produces a more positive flow and discharge of the mercury and enables the material to be more thoroughly subjected to the action of the same. The outer imperforate portions of the spray pipes are preferably arranged in transversely alined bearings of side brackets 14. The brackets 14 are provided with laterally spaced arms or bearing portions between which are arranged the gears 10 which are in the form of sprocket gears and which mesh with a sprocket chain 15 extending beneath and over the sprocket gears or pinions for causing the same to rotate in reverse directions and also to secure the positive mesh between the sprocket chains and the gears 10. The sprocket chain 15 is also trained over a relatively large sprocket wheel 16 mounted on a transverse shaft 17 which extends entirely across the mill and is journaled in suitable bearings thereof. The sprocket gearing is located at each side of the inlet trough or sluice way as clearly illustrated in Fig. 1 of the drawings and the said shaft has also keyed or otherwise fixed to it sprocket gears 18 located at the lower ends of the mercury troughs 13 which are inclined downwardly and rearwardly from the front or inlet end of the mill. The sprocket wheels 18 receive and mesh with chains 19 provided with suitable buckets 20 and forming endless conveyers. The chains 19 also pass over and mesh with gear wheels 21 of a top front transverse shaft 22 which is journaled in suitable bearings and also extending entirely across the mill. The endless conveyers of the top mercury trough extend downwardly to the bottom of the mill and their chains 19 pass beneath and mesh with sprocket wheels 23 located in bottom troughs 24 arranged at opposite sides of the mill as clearly illustrated in Fig. 4 of the drawings. The buckets 20 of the conveyers of the top mercury trough are carried upward from the bottom trough in an upright position for conveying mercury from the bottom troughs to the top mercury trough and the said buckets are inverted over the said top mercury troughs for discharging the contents 65 of the bucket into the top troughs 13. The

buckets travel along the top flights of the chains 19 in an inverted position and descend in such position at the inner or rear flight of the said chains 19 as clearly illustrated in Fig. 4 of the drawings. The front ends of the top mercury troughs are provided with curved front walls 25 to clear the sprocket wheels 18 and the bottoms of the top mercury troughs are provided with depressions or pockets 26 into which the mercury flows and from which the stationary pipes 12 diverge as clearly illustrated in Fig. 2 of the drawings.

The sand and the mercury are thoroughly mixed and the former is completely subjected to the action of the mercury in passing through the baffle casing 3. The sand in the material is spread out in thin sheets in traveling back and forth through the passages of the baffle casing and the top baffle casings are provided with outlets 27 communicating with concentrating casings 28 adapted to concentrate and mix the sand and the mercury to effectually separate the values from the sand. The concentrating and mixing casings 28 are each composed of inner and outer shells 29 and 30 spaced apart to form a relatively narrow intervening passage at each side of each of the casings 28 and having oppositely inclined upper portions 31 and 32 and approximately semi-circular connecting portions 33 and 34. The oppositely inclined portions 31 and 32 of the inner and outer shells diverge downwardly and the spaced curved bottom portions 33 and 34 form a curved bottom space or passage into which extend opposite transversely disposed mercury spray pipes 35 constructed substantially the same as those heretofore described and provided with spur gear wheels 36 which mesh with a large gear wheel 37. The gear wheels 37 of the two sets of spray pipes 35 are mounted on a transverse shaft 38 and the pinions or gears 36 are arranged in a curved series 110 and mesh with the large gear wheels 37. The rotary spray pipes 35 are oppositely inclined and they are connected with fixed pipes 39 extending downwardly from depressions or pockets 39^a of front intermediate mercury troughs 40 located above front intermediate baffle casings 41 with which the mixing and concentrating casings are connected. The front intermediate mercury troughs 40 which are constructed substantially the same as those heretofore described are supplied with mercury from the bottom troughs 24 by an endless conveyer 42 consisting of a series of buckets mounted on a chain 43 which meshes 125 with top front and rear sprocket wheels 44 and 45 and a bottom 46. The bottom sprocket wheels 23 and 46 are mounted on the transverse shaft 47 extending entirely across the mill and journaled in suitable 130

bearings. The buckets of the endless conveyers 42 convey mercury from the bottom troughs to the intermediate front troughs 40 and are inverted over the same for discharging their contents into the said troughs 40. The side troughs 24 are provided with curved bottoms and the buckets pass through the same between the bottoms of the troughs and the gear wheels 23 and 46, as clearly illustrated in Fig. 4 of the drawings. The outer shells 30 of the mixing and concentrator casings are provided with outlets 48 which communicate with the intermediate front baffle casings 41 constructed similar to those heretofore described and provided with horizontal baffle plates 49 terminating short of the opposite ends of the casing to provide horizontal passages with outlets alternately at opposite ends of the casing to cause the material to travel back and forth through the baffle casings 41. The baffle casings 41 are provided with outlets 50 which communicate with connecting troughs or sluice ways 51 extending rearwardly from the baffle casings 41 and located above rear intermediate baffle casings 53 and receiving oppositely inclined transversely disposed rotary mercury spray pipes 54 arranged at an inclination and provided with sprocket pinions 55 and connected by pipes 56 with mercury troughs 57. The top mercury troughs 57 of the rear set are provided with bottom depressions 58 from which the stationary pipes 56 diverge and mercury is supplied to the troughs 57 from side bottom troughs 59 by endless conveyers 60 consisting of buckets mounted on chains 61 arranged on top sprocket wheels 62 and 63 and bottom sprocket wheels 64. The front flights of the sprocket chains of the conveyers have their buckets arranged in an upright position, and the buckets are inverted at the top flight for discharging their contents into the troughs 57. The wheels 62 and 63 are mounted on transverse shafts 65 and 66 and the bottom wheels 64 are mounted on a transverse shaft 67. The shaft 66 carries a gear wheel 68 consisting of a relatively large sprocket wheel receiving a chain 69 which meshes with the sprocket pinions 55 of the spray pipes 54. The connecting troughs 51 discharge into the baffle casings 53 provided with baffle plates 70 and constructed similar to the baffle casings heretofore described. The baffle casings are connected with concentrating and mixing casings 71 composed of spaced inner and outer shells and constructed similar to the casings 28 heretofore described. The mixing and concentrating casings are equipped with mercury spray pipes 72 provided with spur pinions 73 arranged in curved series and meshing with spur gear wheels 74. The spray pipes 72 which are constructed similar to those heretofore described are connected by pipes 75 with depressions or pockets 76 of side mercury troughs 77 located above and at opposite sides of the bottom of the mixing and concentrating casings. The rear mixing and concentrating casings are connected with rear bottom baffle casings 78 constructed similar to those heretofore described and provided with baffle plates 79. The mercury troughs 77 are supplied with mercury from the bottom troughs 59 by endless conveyers 80 having sprocket chains 81 passing over upper sprocket wheels 82 and 83 and under bottom sprocket wheels 84. The buckets of the endless conveyers 80 are inverted over the troughs 77 to discharge their contents into the same. The outlets 85 of the baffle casings 78 communicate with outlet or discharge troughs 86 where the material is discharged after the values are extracted from the same. In practice a screen door suitably locked will be provided to prevent access to the mill at the discharge or outlet trough to prevent unauthorized persons from carrying away any of the values extracted or separated from the material operated on by the mill. The sand passes out through the discharge troughs 86 and the mercury passes through a bottom opening 87 into a depression or pocket 88 and is conveyed by suitable conduits 89 to the bottom troughs 59. The bottom troughs 59 are connected by suitable pipes 90 with the front bottom troughs 24 and the said bottom troughs 24 and 59 are provided with suitable valved outlets 91 for enabling the mercury to be drawn off as required. The passages or conduits 89 are preferably portions of the bottom baffle casings but the mercury may be returned to the front and rear bottom side troughs 24 and 59 by any other suitable means. The main casing or housing of the mill is designed to be provided with suitable doors and means for locking the same. The mill is shown composed of two units each consisting of two pairs of side mercury troughs, and two sets of baffle casings. Any number of the units may of course be employed. The mill is operated by any suitable power which may be connected with the mill by sprocket gearing comprising a sprocket chain 92 and a large sprocket wheel 93 mounted on the shaft 38. The shaft 38 is connected by a suitable sprocket gearing 94 with the shaft 17 and suitable sprocket gearing 95 connects the shaft 38 with the rear shaft 96 of the endless conveyers 80 and sprocket gearing 97 connects the shaft 96 with the rear shaft 66 of the conveyers 60. The front sprocket wheels 44 are mounted on a transverse shaft 98 and the front sprocket wheels 82 are mounted on the transverse shaft 99. The gearing for transmitting motion from the driving shaft 38 to the various shafts may

be arranged in any other desired manner and any suitable gearing may of course be employed for this purpose. The mercury may be used continuously until the desired 5 amount of values has been obtained.

Any suitable means may be employed for tightening the chains or belts and in practice each bearing will be equipped with a suitable drip receptacle 100 and pipes 101 10 will be employed for conveying the oil to the desired point to prevent the same mixing with the mercury. Also the bottom opening 87 will be provided with a suitable apron 102 adapted to prevent the sand from 15 following the mercury back to the bottom tanks or reservoirs 24 and 59.

What is claimed is:—

1. An amalgamator mill including a conduit for the material operated on, a plurality of rotary spray pipes extending into the conduit and located at intervals, a mercury receptacle connected with the spray pipes and means for rotating the spray 20 pipes.

2. An amalgamator mill including a conduit for the material operated on in the mill, inclined spray pipes extending into the conduit from opposite sides thereof, upper mercury troughs located above the said conduit 30 and communicating with the spray pipes, means for conveying mercury to the upper mercury troughs and means for rotating the spray pipes.

3. An amalgamator mill including a conduit for the material operated on in the mill, oppositely inclined rotary spray pipes extending into the conduit and provided with gear wheels, mercury troughs located above the spray pipes and provided with relatively 35 fixed pipes communicating with the spray pipes, an endless carrier for conveying mercury to the mercury troughs, and gearing for operating the endless carrier and for rotating the spray pipes.

4. An amalgamating mill including a conduit for the material operated on and a ro- 40

tary spray pipe extending into the passage, means for supplying mercury to the spray pipe, and means for rotating the said spray pipe. 50

5. An amalgamator mill including a mixing and concentrating casing comprising inner and outer shells having oppositely inclined upper portions and curved lower portions, said shells being spaced apart to provide intervening passages and a curved series of spray pipes extending into the space between the bottom portions of the inner and outer shells. 55

6. An amalgamator mill including upper 60 and lower baffle casings spaced apart and having baffle plates for causing the material operated on in the mill to travel back and forth to the casings and a mixing and concentrator casing connecting the baffle casings 65 and communicating with the same, said mixing and concentrator casing comprising inner and outer shells, spaced apart to provide opposite side passages and a connecting bottom passage. 70

7. An amalgamator mill including a plurality of baffle casings provided with baffle plates, concentrating and mixing casings arranged between and connected with the baffle casings, rotary spray pipes arranged in 75 the path of the material, mercury troughs located at opposite sides of the mill and located above the spray pipes and connected therewith, means for rotating the spray pipes, bottom troughs connected with each 80 other and with the lowermost casing, and endless conveyers extending from the bottom troughs to the mercury troughs and having flights passing over the same and discharging into the said mercury troughs. 85

In testimony whereof I affix my signature in presence of two witnesses.

DAVID L. PENROD.
